Primary Examiner — Ryan Harvey

(57) **CLAIM**

The ornamental design for a training apparatus as shown and described.

DESCRIPTION

1. Training apparatus

1.1 is a perspective view of a training apparatus.

1.2 is a front view thereof.

1.3 is a back view thereof.

1.4 is a right view thereof.

1.5 is a left view thereof.

1.6 is a top view thereof.

1.7 is a bottom view thereof.

The features shown in broken lines in the drawings depict environmental subject matter only, and form no part of the claimed designs.
